CHAIR

Robert M. Nelson, Lombard, Ill.

Application March 14, 1951, Serial No. 14,482

Term of patent 14 years

(Cl. D15—8)

To all whom it may concern:

Be it known that I, Robert M. Nelson, a citizen of the United States, residing at Lombard, county of Du Page and State of Illinois, have invented a new, original, and ornamental Design for a Chair, of which the following is a specification, reference being had to the accompanying drawing, forming a part thereof, in which:

Figure 1 is a perspective view of a chair showing my new design; Fig. 2, a front elevational view; Fig. 3, a side elevational view; Fig. 4, a broken rear elevational view; and Fig. 5, a top plan view.

I claim:

The ornamental design for a chair, as shown.

ROBERT M. NELSON.
